Primary Examiner — Paula Greene(74) *Attorney, Agent, or Firm* — Blank Rome, LLP(57) **CLAIM**

The ornamental design for a speakerphone, as shown and described.

DESCRIPTION

FIG. 1 is a perspective view showing a top, a front, and a left side of a speakerphone according to our new design; FIG. 2 is an elevational view of the front of the speakerphone; FIG. 3 is an elevational view of a back of the speakerphone; FIG. 4 is an elevational view of the left side of the speakerphone;

FIG. 5 is an elevational view of a right side of the speakerphone; and

FIG. 6 is a plan view of the top of the speakerphone; and, FIG. 7 is a plan view of a bottom of the speakerphone.

The broken lines showing in FIGS. 1-5 and 7 are for illustrative purposes only and form no part of the claimed design. The grid of circular apertures schematically depicted in FIGS. 1-6 is continuous throughout the surfaces on which the apertures are shown.

1 Claim, 4 Drawing Sheets(56)
